UNITED STATES PATENT OFFICE

2,005,307

APPARATUS FOR COATING METAL STRIPS

Thomas D. Williams, Garfield Heights, Ohio,
assignor to The American Steel and Wire Company of New Jersey, a corporation of New Jersey

Application April 11, 1933, Serial No. 665,618

1 Claim. (Cl. 91—30)

This invention relates to an apparatus for coating metal strip, and more particularly to coating flat strip steel or other shapes which have previously been lacquered or varnished.

5 One object of the present invention is the provision of a novel apparatus for coating previously lacquered or varnished and baked metal strip with liquid wax or other suitable coating material, in such manner as to provide an additional 10 moisture repellent medium, and a strip with a harder and smoother finish.

Another object is the provision of a novel method and apparatus for coating continuously fed metal strip with determined quantities of 15 coating liquid at determined intervals, together with means for evenly distributing the coating and removing the surplus.

These and further objects will appear after referring to the drawings, in which:

20 Figure 1 is a plan of the apparatus of the invention.

Figure 2 is a side elevation thereof.

Figure 3 is a sectional elevation of the improved 25 coating material dispensing apparatus of the invention.

Figure 4 is a sectional view of the line IV—IV of Figure 3.

Figure 5 is a sectional view of the line V—V of 30 Figure 3.

25 Referring more particularly to the drawings, the numeral 2 designates a bed over which metal strip A is continuously fed from the baking furnace of a conventional lacquering or varnishing apparatus (not shown). A cylindrical stationary shell 3 is mounted transversely of the bed 2 and provided with dispensing apertures 3^a which are positioned immediately above the metal strip A. A rotary shell 4 is journaled in the stationary shell 3 and provided with a plurality of apertures 4^a 35 which are adapted to be aligned with the dispensing apertures 3^a in the stationary shell 3, and a feed orifice 5.

40 A ratchet 6 is secured to the rotary shell 4 and a rocking lever 7 journaled thereon. A pawl 7^a is mounted on the rocking lever 7 for engaging the ratchet 6. A motor 8 is mounted on the bed 2 for driving a gear reducing unit 9 which is provided with a crank 10. A connecting-rod 45 12 is connected to the crank 10 at one of its ends and provided with a sliding crank pin 14 which is adjustably connected to the rocking lever 7.

45 A suitably heated storage tank 15, for containing liquid wax or paraffin or other coating material, is disposed adjacent the stationary cylindrical shell 3 and provided with a feed pipe 16 and adjusting valve 16^a for supplying the latter with the material at a point accessible to the feed orifice 5 in the rotary shell 4. A steam pipe 17

is internally disposed throughout the length of the rotary shell 4 for maintaining the coating liquid in solution and at the proper temperature.

5 A pair of wipers 19 is mounted transversely of the bed 2 on either side of the metal strip A and in contact therewith, and a drip pan 20 disposed beneath the wipers, and a substantial portion of the bed, for returning surplus coating liquid through a conduit 21 to the storage tank 15.

10 In operation, metal strip A is continuously fed over the bed 2 as it emerges from the baking furnace (not shown) and the motor 8 continuously operated to reciprocate the rotary shell 4. The coating fluid from the tank 15 will flow through the feed pipe 16 and collect in the rotary shell 15 4, due to the periodic alinement of the feed orifice 5 with the feed pipe. As the rotary shell rotates, the apertures 4^a therein will align with the dispensing apertures 3^a in the stationary cylindrical shell 3, permitting the coating liquid to 20 drip on the strip A as it moves across the bed. As the strip progresses between the wipers 19 the coating liquid will be evenly distributed and the surplus caused to drop into the drip pan 20 and return through the conduit 21 to the storage 20 tank 15.

25 The sliding crank pin 14, due to its adjustment relative to the rocking lever 7, and the liquid supply adjusting valve 16^a, provide for effective regulation of the apparatus.

30 While I have shown and described one specific embodiment of my invention, it will be understood that I do not wish to be limited exactly thereto, since various modifications may be made without departing from the scope of my invention, as defined in the following claim.

I claim:

35 Apparatus for coating metal strip comprising a stationary cylindrical shell having a plurality of dispensing apertures, a coating material supply conduit for said stationary cylindrical shell, a rotary shell journaled in said first named shell and having a plurality of apertures adapted for periodic alinement with said dispensing apertures 40 and at least one feed orifice adapted for periodic alinement with said coating material supply conduit, a ratchet secured to said rotary shell, a rocking lever journaled on said last named shell and having a pawl for engaging said ratchet, a connecting-rod adjustably secured to said rocking lever, means for reciprocating said connecting-rod, means for evenly distributing the coating material from said dispensing apertures on 45 said metal strip and removing the surplus therefrom, 50 a coating material storage container for said supply conduit, and means for returning the surplus coating material to said storage container.

THOMAS D. WILLIAMS,
